UNITED STATES PATENT OFFICE.

FREDERICK C. FROELICH, OF PHILADELPHIA, PENNSYLVANIA.

AIR PUMP.

Application filed November 23, 1922. Serial No. 602,704.

To all whom it may concern:

Be it known that I, FREDERICK C. FROELICH, a citizen of the United States, residing in the city and county of Philadelphia, State 5 of Pennsylvania, have invented a new and useful Air Pump, of which the following is a specification.

My invention relates to an air pump and consists of barrels, pistons therein, air inlet 10 valves an air outlet valve, and means for operating said pistons by the action of a cam or cam body whereby air in large volumes may be drawn into the barrels and in a measure compressed therein and then 15 forcibly discharged therefrom in continuous flow to a place of service.

The invention is satisfactorily illustrated in the accompanying drawing, but the important instrumentalities thereof may be 20 varied, and so it is to be understood that the invention is not limited to the specific details shown and described, as long as they are within the spirit or scope of the claims.

Figure 1 represents a longitudinal section 25 of an air pump on line 1—1 Figure 2, embodying my invention.

Figure 2 represents a transverse section thereof on line 2—2 Figure 1 on a reduced scale.

30 Figure 3 represents a transverse section thereof on line 3—3 Figure 1.

Figure 4 represents a side elevation of the cam or cam body detached.

35 Figure 5 represents a section thereof on line 5—5 Figure 4.

Figure 6 represents a transverse section of the housing of the pump detached from 40 position.

Figure 7 represents a longitudinal section 45 of another embodiment of the invention on line 7—7 Figure 8.

Figure 8 represents a transverse section thereof on line 8—8 Figure 7, on a reduced scale.

45 Figure 9 represents a transverse section thereof on line 9—9 Figure 7, on a reduced scale.

Figure 10 represents a side elevation of the cam or cam body detached from Figure 50 7 on the scale of Figures 8 and 9.

Similar numerals of reference indicate corresponding parts in the figures.

Referring to the drawings.

1 designates a housing formed of a cast 55 ing which is surrounded by the inclosing

casing 2, the forward end of which is secured to the flange 3 on the corresponding end of the housing by suitable screws which are passed through said casing into said flange. In said housing are chambers forming a series of longitudinally extending barrels 4 which extend in circular form around said housing and receive the pump pistons 5 which are movable in said barrels. Projecting from said flange 3 is the neck 6 60 which is hollow forming continuations 7 of the chambers of the barrels, the pistons being shorter than the entire lengths of the barrels so that they may have sufficient throws therein in opposite directions. 70

In the outer walls 8 of the barrels for a portion of the length thereof within the casing 2 are the longitudinally extending slots 9 in which are received the rollers 10 which are mounted on the pins 11 secured 75 to the pistons and extending transversely through the pistons and are outturned to the exterior of the same where they have said rollers 10 secured in them. Surrounding the barrels 4 within the casing 2 is what 80 I term the rotatable cam 12 which consists of a cup-shaped body having one end closed by the wall 13, and the opposite end open, said wall having thereon the hub 14 which is firmly connected with the shaft 15, the 85 latter passing through the central opening 16 in the housing 1 as its bearings.

On the end of the housing opposite to the casing 2 is the head 17 which is cast with the housing and is hollow forming the air 90 discharging chamber 18, the inner wall 19 of which has therein the series of ports 20 which are in communication with the barrels 4 respectively, the walls of said ports forming seats for the ball or other valves 21 95 which are adapted to open outwardly into or towards the chamber 18 so that air pumped into the barrels may be discharged therefrom into the chamber 18, the head having connected with it on its exterior the 100 nozzle 22 which is in communication with the chamber 18 and adapted to direct the air to a place of service.

The valves 21 are held to their seats by the engaging coil or other springs 23 which 105 occupy the chamber 18 and are connected with and held in place by the plugs 24 which are screwed to the outer wall of the head 17.

In the neck 6 are the ports 25 one for 110

each barrel, the same being in communication with the interior of the barrels respectively and with the interior of the plugs 26 whose bodies are screwed to the collars 5 27 on the neck 6 and in which are chambers for the inwardly opening ball or other valves 28, the seats of the latter being on the bases of the air inlet ports 29 in said plugs. Said valves 28 when in closed positions are 10 held on their seats by the springs 30 which rest upon the adjacent portions of the necks 6 and bear against said valves 28.

In the inner face of the side wall of the 15 cam or cam body 12 is the spiral groove 31 in which are received portions of the rollers 10 carried by the pins 11 on the pistons 5 as has been stated.

The operation is as follows:

Power is communicated to the shaft 15 of 20 the pump in any suitable manner, thus rotating the cam 12 whereby the rollers 10 which are engaged in the spiral groove 31 and the pins 11 which are attached to the pistons 5 cause the latter to be reciprocated 25 in the barrels. In one throw of the pistons which in the present case is to the right, open the valves 28 and close the valves 21. Air is thus drawn in large volumes into the barrels through the ports 29 and 25 following the 30 throw of the pistons. Then the piston returns making the opposite throw when the valves 28 are forced on their seats and so closed to the atmosphere but the valves 21 are forced from their seats and open into the 35 chamber 18 when the air is forcibly injected into the latter and from thence directed by the nozzles 22 to a place of service, there being a continuous flow of air from the pump with great pressure.

40 In Figures 7, 8, 9 and 10 which show another embodiment of my invention, the cam or cam body is of the form of the collar 32 having thereon hubs 33 which are secured to an operating shaft similar to the shaft 45 15 in the prior figures, but the exterior surface of the collar has therein the spiral groove 34 to receive the rollers 35 which are secured to the ends of the pins 5 which are extended inwardly from the pistons 11, but 50 the operation of the pump in this instance is similar to that shown and described in Figures 1-5 inc. Referring to Figure 7 on the exterior of the housing 1 is a series of ribs 36 radiating from said housing and 55 separated from each other forming surfaces beyond said housing adapted to cool said housing.

The pump in either case will be found admirably adapted for the purpose of inflating tires and other services in garages to which uses, however, I do not limit myself.

Having thus described my invention what I claim as new and desire to secure by Letters Patent, is:

1. An air pump comprising in combination, a housing having a central cam case and concentrically arranged surrounding cylinders each having an elongated slot at one end and provided with a valved inlet and a valved outlet at its other end, a piston arranged within each cylinder, a rotatable cam mounted within said cam case, means for operating said cam and means including pin and roller connections passing through the cylinder slots and connecting said cam with each of said cylinders for reciprocation thereof. 65

2. An air pump comprising in combination, a housing having a central cam case and concentrically arranged surrounding cylinders each having an elongated slot at one end and provided with a valved inlet and a valved outlet at its other end, each valved inlet being disposed at right angles to the horizontal axis of a cylinder, a piston arranged within each cylinder, a rotatable cam mounted within said cam case, means for operating said cam and means passing through the cylinder slots and connecting said cam with each of said cylinders for reciprocation thereof. 80

3. An air pump comprising in combination, a housing having a central cam case and concentrically arranged surrounding cylinders each having an elongated slot at one end and provided with a valved inlet and a valved outlet at its other end, each valved outlet being disposed in parallelism with the horizontal axis of said cylinders, a piston arranged within each cylinder, a rotatable cam provided with a grooved exterior said cam being mounted within said cam case, means for operating said cam and means including pin and roller connections passing through the cylinder slots and connecting said cam with each of said cylinders for reciprocation thereof, each pin passing through and being fixed to a piston and each roller tracking in said cam groove. 95

4. An air pump comprising in combination, a housing having a central cam case and concentrically arranged surrounding cylinders each having an elongated slot at one end and provided with a valved inlet and a valved outlet at its other end, a piston arranged within each cylinder, a chamber arranged at the discharge end of said housing for direct reception of air as compressed in all of said cylinders, a rotatable cam mounted within said cam case, means for operating said cam and means including pin and roller connections passing through the cylinder slots and connecting said cam with each of said cylinders for reciprocation thereof. 115

5. An air pump comprising in combination, a housing having a central cam case and concentrically arranged surrounding

cylinders each having an elongated slot at one end and provided with a valved inlet and a valved outlet at its other end, each valved inlet being disposed at right angles to the horizontal axis of a cylinder, a piston arranged within each cylinder, a rotatable cam having a cam groove mounted within said cam case, means for operating said cam and means including a roller for cooperative- ly engaging said cam groove passing through the cylinder slots and connecting said cam with each of said cylinders for reciprocation thereof.

FREDERICK C. FROELICH.
